UNITED STATES PATENT OFFICE.

WILLIAM W. JARRETT, OF MAYSVILLE, ALABAMA, ASSIGNOR OF ONE-HALF
TO JOHN M. HAMPTON, OF NORMAL, ALABAMA.

DESIGN FOR A WASHBOARD.

SPECIFICATION forming part of Design No. 35,146, dated October 1, 1901.

Application filed August 27, 1901. Serial No. 73,503. Term of patent 14 years.

To all whom it may concern:

Be it known that I, WILLIAM W. JARRETT, a citizen of the United States, and a resident of Maysville, in the county of Madison and State of Alabama, have invented and produced a new and original Design for a Washboard, of which the following is a specification, reference being had to the accompanying drawing, forming a part thereof, in which the figure of the drawing is a perspective view of a washboard embodying the features of my design.

The leading features of the design consists of the front concavity and rear convexity of the central portion of the side bars A, the feet B at the bottom of the side bars, which incline downward and rearward, and the box-receptacle C at the upper portion of the side bars, the front whereof is open and the back inclined upward and rearward at a more or less acute angle to the upper rear portions of the side bars.

The minor features of the design consist in the rollers D, extending from one side bar A to the other from a point just above the feet B to a point below and removed from the box-receptacle C, so that a wide space E is obtained between the uppermost roller and the box-receptacle.

Having thus described my invention, I claim as new and desire to secure by Letters Patent—

The design for a washboard herein shown and described.

In testimony whereof I have signed my name to this specification in the presence of two subscribing witnesses.

WILLIAM W. JARRETT.
